UNITED STATES PATENT OFFICE.

NEWTON H. FOGG, OF SANFORD, MAINE.

DESIGN FOR A FLY-KILLER.

41,606.

Specification for Design.

Patented July 25, 1911.

Application filed January 29, 1909. Serial No. 475,086. Term of patent 3½ years.

To all whom it may concern:

Be it known that I, NEWTON H. Fogg, a citizen of the United States, residing at Sanford, in the county of York and State of Maine, have invented a new, original, and ornamental Design for a Fly-Killer, of which the following is a specification, reference being had to the accompanying drawing, forming part thereof.

Figure 1 is a side view of a fly killer showing my new design. Fig. 2 is a face

view of the fly killer, and Fig. 3 is a vertical central cross section of the upper portion thereof.

I claim:

The ornamental design for a fly killer, as shown.

NEWTON H. FOGG.
